UNITED STATES PATENT OFFICE.

GEORGE MAAG, OF AKRON, OHIO, ASSIGNOR TO THE XXTH CENTURY HEATING AND VENTILATING COMPANY, OF AKRON, OHIO, A CORPORATION OF OHIO.

FURNACE-RADIATOR.

No. 813,507.

Specification of Letters Patent.

Patented Feb. 27, 1906.

Application filed May 26, 1905. Serial No. 262,399.

To all whom it may concern:

Be it known that I, GEORGE MAAG, a citizen of the United States, residing at Akron, in the county of Summit and State of Ohio, have invented new and useful Improvements 5 in Furnace-Radiators, of which the following is a specification.

My invention has relation to radiators for hot-air furnaces.

10 The object of my invention is to provide a radiator primarily designed for use in connection with furnaces intended to burn gas, wood, and anthracite coal, wherein the proper circulation of the products of combustion will be through a long series of circuitous flues to accomplish as great a diffusion as possible of the heat carried by the products of combustion and also to provide in connection with said radiator means whereby the 15 products of combustion may, in one instance, be carried directly through the flues to the offtake-flue without further circulation therein.

The invention also aims to provide means 20 for simultaneously opening all the flues in the radiator to the passage of the products of combustion, thus shortening the length of travel of the said products and increasing the draft of the furnace thereby.

25 The invention further aims to provide means for opening the before-mentioned flues, which will be simple and easily reached from a charging-door of the furnace at any time, so that the flues may be readily accessible 30 for the purpose of cleaning, as well as to open them to the passage of the products of combustion to the uptake-flue.

The invention consists, essentially, in providing a hollow cylindrical drum, through 35 which is a concentric opening for the passage of the heated air from the lower portions of the casing through the radiator to the upper portions thereof, as well as a passage around the inside of the radiator for the products of combustion, and in making the concentric opening for the passage of the heated air extend in the form of a broken circle, the point where the break occurs in this circle being the point where the fuel is fed to the fire-pot.

40 The invention further consists in providing the space between the walls of the radiator with a series of circumferentially-arranged baffle-plates so disposed that the 45 products of combustion after leaving the fire-

pot will pass either in a direct course to the 55 offtake-flue or, if desired, in a circuitous manner thereto. In accomplishing this it is designed to have the products of combustion leave the fire-pot on either side of the charging-door and there enter the circumferential 60 flues, thus compelling, as far as possible, the filling of the entire combustion-chamber of the furnace with the products of combustion before they depart therefrom.

With the foregoing and other objects in 65 view the invention consists of the novel construction, combination, and arrangement of parts constituting the radiator, to be herein-after referred to, and illustrated in the accompanying drawings, which form a part of 70 this specification, in which is shown the preferred embodiment of the invention; but it is to be understood that changes, variations, and modifications can be resorted to which come within the scope of the claim hereunto 75 appended.

In the drawings, wherein like reference characters denote corresponding parts throughout the several views, Figure 1 is a perspective view of a furnace with the casing thereof 80 in dotted lines and a portion of the outer shell of the radiator broken away to better illustrate the interior thereof. Fig. 2 is a vertical central section of the radiator at the line X of Fig. 3, and Fig. 3 a horizontal section at the line Y of Fig. 2.

Referring to the drawings, 1 represents the outer wall of the lower portion of the furnace, wherein is situated the ash-pit to, which access is had by means of the door 2, and upon 90 this portion of the furnace is mounted a casing-ring 3, which is designed to support the upper casing. (Illustrated in the drawings by dotted lines and designated by the numeral 4.) This furnace is provided with the ordinary 95 fire-pot and grate over the ash-pit constituting a heater for the device; but as these elements are not essential to the understanding of this invention they are not shown, and upon the fire-pot of this device is mounted 100 my improved radiator. This radiator consists of a cast-iron top member 5 and bottom member 6, and extending between these members and surrounding the mechanism herein-after described is an external casing 7. 105 The bottom member 6 of the radiator is provided with a central opening surrounded by a downwardly-extending flange adapted to

project into the fire-pot, whereby communication is established with the heater of the device, and this downwardly - extending flange also serves to sustain and steady the 5 radiator. The external casing 7 of the radiator is formed from continuous sheet metal, excepting where it is interrupted in front by the pouch 8, which leads from the charging-doors 9 in the outer shell 4 to the heater. In 10 the top and bottom members 5 and 6 are elongated apertures registering vertically with each other and substantially concentric with the general outlines of the radiator. Extending between the top and bottom 15 members 5 and 6 is a second casing located adjacent these elongated apertures and conforming in outline to them, whereby there is formed an opening 10. The outer portion of this second casing is designated in the 20 drawings by the reference-numeral 11 and the inner portion by the reference-numeral 12, and these two portions are united at their ends by curvilinear portions 14. These walls 11 and 12 constitute the shell of the upwardly-extending air-heating flue 10. The 25 space inclosed by the wall 12 of the second casing and covered at the top by the member 5 constitutes a heating-chamber of the device and is in open communication with the heater thereof through the aperture in the bottom member 6. The space existing 30 between the outer wall 11 of the second casing and the external casing 7 forms a second heating-chamber of my improved radiator, and this second heating-chamber is also in 35 open communication with the heater of the device through the space existing around the curvilinear portions 14 of the second casing.

It will be stated that the top and bottom 40 members of the radiator are held together and clamped upon the external casing 7 by means of stay-bolts 13, which may be placed at any location where necessary throughout the body thereof.

45 From the rear portion of the external casing 7 of the radiator there leads a direct outlet-flue 15, which is provided with an ordinary damper 16 (see Fig. 2) and is connected with a second outlet 17, which takes off from the lower portion of the casing 7. This second outlet 17 is generally provided with a check-damper 18, which is of the ordinary construction.

In order to cause the products of combustion, which arise from the heater and pass around the curvilinear ends 14 of the second casing and enter the second heating-chamber, to travel a circuitous path and to distribute as much of their heat as possible, I provide in the second heating-chamber between the wall 11 and the external casing 7 a plurality of circumferential baffle-plates. I find that in placing these baffle-plates the best arrangement consists in providing two upper 55 baffle-plates 19, extending from near the cur-

vilinear portions 14 on both sides of the radiator to near the opening where the outlet-flue 15 is attached to the casing 7; but their ends are separated a slight distance, forming an opening to permit the products of combustion to pass over their upper surfaces and to then turn downwardly and return toward the charging-doors 9. Below the baffle-plates 19 I place a second elongated baffle-plate 20, whose ends start a greater distance from the 70 curvilinear portions 14 than do the ends of the baffle-plates 19. This baffle-plate 20 extends circumferentially through the space between the casing 7 and wall 11 and approximately midway between the baffle-plates 19 75 and the bottom member 6. In order to make the second heating-chamber as long as possible and to cause the products of combustion to go over the top of the baffle-plates 19, I place upwardly-extending baffle-plates 21 on the member 6, which is provided with steady-lugs 22, and I sustain their upper ends by means of removable pins 23, which pass through the baffle-plates 19, as well as the baffle-plates 21. 80

It will be seen from the foregoing that the products of combustion will pass from the fire-pot in the direction of the arrows in Fig. 1, over the baffle-plates 19 and around their rear ends, and from thence around the front 90 ends of the baffle-plate 20 and from thence under the baffle-plate 20 to the outlet 17. It will be further seen that it will be necessary in order to cause this passage of the products of combustion around these various baffle-plates that the damper 16 in the outlet 15 must be in the position shown in Fig. 2; otherwise the products of combustion will pass directly out the outlet 15 and not traverse the path just described for them. It is also 95 apparent that after the baffle-plates 21 are removed, which may be easily done by reaching into the charging-doors, the products of combustion will pass directly through the second heating-chamber to the outlets. 100

When it is necessary to clean the baffle-plates 19 and 20 and the upper part of the member 6 between the casing 7 and wall 11 and the flues existing therebetween, the baffle-plates 21 are withdrawn by removing the 115 pins 23 and lifting them out through the charging-doors. Then a suitable utensil may be employed to remove any accumulation therein contained.

What I claim, and desire to secure by Letters Patent, is—

A radiator comprising a heating-chamber adapted to be placed in communication with a heater, a second heating-chamber surrounding said first-mentioned heating-chamber 125 and in open communication therewith, said chambers being formed by top and bottom members, each of said members being provided with an elongated aperture adapted to register each with the other, an external cas- 130

ing connecting said top and bottom members, a second casing connecting said top and bottom members, located adjacent to said elongated apertures and forming in connection therewith an air-heating flue through said radiator, said bottom member being provided with a second aperture to adapt the first-mentioned heating-chamber to be placed in communication with a heater, the second heating-chamber being provided with two outlets therefrom, a plurality of baffle-plates arranged in said second heating-chamber in planes parallel with said top and bottom members, one of said baffle-plates being elongated and spaced from the bottom member

to form flues in communication with one of said outlets, the others of said baffle-plates being located between the top member and said elongated baffle-plate and extended over the respective ends thereof to form flues and removable baffle-plates connecting said last-mentioned baffle-plates with said bottom member. 20

In testimony whereof I have hereunto set my hand in presence of two subscribing witnesses. 25
